UNITED STATES PATENT OFFICE.

SELAH M. BAIRD, OF HOLLY, MICHIGAN, ASSIGNOR OF ONE-HALF TO JOHN M. BAIRD, OF SAME PLACE.

LIFTING-JACK.

SPECIFICATION forming part of Letters Patent No. 244,521, dated July 19, 1881.

Application filed April 15, 1881. (No model.)

To all whom it may concern:

Be it known that I, SELAH M. BAIRD, a citizen of the United States, residing at Holly, in the county of Oakland and State of Michigan, have invented a new and useful Lifting-Machine and Wagon-Jack Combined, of which the following is a specification.

This invention has relation to improvements in lifting-jacks; and it consists in the construction and novel arrangement of the several parts hereinafter more fully described.

In the accompanying drawings, Figure 1 represents a perspective view of my improved lifting-jack. Fig. 2 represents a front view of the same, and Fig. 3 represents a rear view.

A designates the base of the jack, to which is secured and arising therefrom a post or standard, B, the upper end of which is provided with a slot, b, and the lower portion thereof has secured thereto the upper ends of brace-bars b', while the lower ends of said bars are secured to the base A. Said standard B is further provided on its face and near the lower portion with a horizontal bar, C, the neck or stem c' of which is screwed or driven in said standard, and is provided with a vertical slot c, and at the rear with a spring-catch or hook, D, projecting obliquely therefrom.

E represents the operating-lever, the forward end of which is pivoted to a vertical bar, e, and having its fulcrum in the vertical slot b, as at e'. Said bar e has attached loosely thereto a projecting arm, F, in the inner end of which is formed a slot, f, through which passes the bar e.

G indicates a stationary bar, the upper end of which is secured to the top of the standard B and the lower end to the base A. Said bar is provided with the projecting arm g, similar in construction to the arm F, said bars G and e being arranged parallel with each other.

Having described the construction of my invention, I will now explain the manner in which it is operated.

45 In raising weights the projecting arm F is

placed under the weight to be raised, when the operating-lever E is brought downward so as to elevate the weight to the required height, or it may be elevated so that the lever E may be held in position by the spring-latch D. 50 Should it become necessary to give the lever a second stroke, the arm g is raised sufficiently to come in contact with the object thus held by the arm F, after which the spring-catch is released from engagement with the lever and the handle raised, thereby lowering the bar e and permitting the projecting arm F to be raised somewhat higher than its former position, (at the same time the weight is supported upon the arm g,) after which the lever is given the 60 second stroke, thereby raising the weight and releasing the same from the arm g and leaving the weight resting on and supported by the arm F. At the same time the lever is caught and held by the spring-catch. 65

It will thus be observed by the foregoing description that I construct a lifting-jack the projecting arms F g of which, being adjustable, can be worked alternately in giving the lever one or more strokes. At the same time 70 it is simple in construction, durable, and easily operated.

Having described this invention, what I claim, and desire to secure by Letters Patent, is—

1. In a lifting-jack, the rigid bar G, provided with the resting-bar g, substantially as shown and described, and for the purposes set forth.

2. The bar G, provided with the sliding arm 80 g, in combination with the bar e, arm F, lever E, base A, and standard B, as set forth.

3. The combination of the catch D, lever E, bar e, arm F, bar G, and arm g with the base A and standard B, as set forth.

SELAH M. BAIRD.
